UNITED STATES PATENT OFFICE

GEORGE BROWN AND FREDERICK S. BROWN, OF BOSTON, MASSACHUSETTS

BED

Application filed November 21, 1927. Serial No. 234,611.

This invention relates to beds and more particularly to that class of beds known as "day beds", wherein the bed comprises a main bed section and a swinging bed section, providing a day bed structure when the sections are together and a full size double bed when the swinging section is extended relative to the main bed section.

Heretofore with day beds having a swinging bed section it has been an extremely difficult operation to move the swinging section from its position overlying the main bed section to an extended position to increase the width of the bed. This has been due largely to the use of improper connecting means between the sections permitting this relative movement, as well as to the failure to provide fixed head and foot extensions for the framework of the swinging bed sections which serve as handles that may be grasped by the operator to facilitate opening the bed. It has been common practice to grasp the spring fabric for opening as well as closing the bed sections, which of course was highly objectionable for the reason that the use of such as a handle is not only uncomfortable and liable to cut the hands, but such practice served to weaken the fabric, thereby stretching and impairing the quality of the spring as a supporting structure for the mattress. Another common practice has been to provide a movable bed section with handles upon the end frame structures adjacent the inner side of the section, necessitating the operator to bend over and while in this uncomfortable position to exert an upward pull on the section as well as an outward pull to open the bed. Moreover, with such constructions it has been necessary for the operator to stand directly in front of the bed so that he could reach the handles to extend the movable section. In such position the operator has been directly in the path of the moving section and not infrequently has been struck by the frame structure of the section while opening the bed. With our improved bed construction the operator may stand at either end of the bed or several feet in front of it, and by simply grasping either of the head or foot extensions and exerting a slight outward pull, open the

bed to its full size position. It has also been common practice to provide the front side rail of the swinging bed section with a handle located midway between the ends thereof to assist in opening the bed. Normally this handle is concealed by the bed covering and aside from the fact that the operator must first lift the covering to locate the handle and bend over to grasp it, it requires considerable effort to pull the section outwardly. Heretofore, relatively short links and other means have been employed to connect the ends of the bed sections so as to permit their relative movement, which obviously, provided a relatively short leverage adding materially to the difficulty of opening the bed, due to the fact that an upward, as well as an outward pulling force, had to be exerted in order to extend the swinging section. The resistance offered by the swinging section when an attempt was made to extend it was materially increased by reason of the fact that the side rail at the inner end of the swinging bed section was directly connected with the links. With such a construction it will readily be seen that the pulling force exerted by the spring fabric upon the end rails of the movable section of the bed was transmitted directly to the pivotal connection between the swinging links and the section through the medium of the side rail and the swinging links. This of course, caused a binding action at the pivotal points, making it extremely difficult to swing the movable bed section to or from a closed position. Moreover, with swinging bed constructions of the prior art, it has been impossible to employ a long connecting member without materially increasing the height of the bed when the sections are together.

Our invention has for its objects to overcome these serious mechanical defects of the previous bed structures and to provide a construction which overcomes the various objectionable features of the bed structures of the prior art, an important object being to provide connecting means between the main bed section and the swinging bed section permitting the latter to be moved relative to the former with a free and easy motion, there being no frictional or binding action at the

pivotal connections between said means and the swinging bed section. Our construction permits the swinging bed section to be moved relative to the main bed section by simply exerting a sidewise pull upon the swinging section whereby the bed may be opened from a closed to the full size position with the least possible effort.

Another object of the invention is to employ section interconnecting means in the form of relatively long swinging links which extend in a substantially vertical plane irrespective of the relative positions of the bed sections, whereby the height of the bed will not be increased when in closed position, said swinging links having high pivotal connections with the swinging bed section.

Another object of the invention is to provide the swinging bed section with head and foot extensions which serve as handles to facilitate opening the bed, and which likewise prevent the mattress from stretching and becoming displaced longitudinally from the bed section; it being another object of the invention to provide the bed sections with a folding mattress having at its opposite ends pockets in the form of extensions or flaps which conceal the head and foot extensions of the swinging bed section and also conceal the frame work at the ends of the bed sections when the sections are together. These pockets additionally prevent sidewise movement of the mattress relative to the bed section and spring, thereby eliminating the necessity of tying or stitching the mattresses to the spring fabric, as has been the common practice heretofore.

Other objects of the invention will appear in the following specification when read in conjunction with the accompanying drawings.

In the drawings,

Fig. 1 is a perspective view of our improved bed structure with the bed sections thereof together.

Fig. 2 is a perspective view showing the bed in its extended position of use.

Fig. 3 is a side elevation of our complete bed structure in closed position showing the improved mattress thereupon.

Fig. 4 is an end elevation, partly in section, of the bed and mattress illustrating the manner in which the mattress is folded.

Fig. 5 is a detail sectional view showing the relationship of the mattress pockets and flaps with the head or foot extensions of the swinging bed section.

Fig. 6 is a detail sectional view taken substantially along the line 6—6 of Fig. 1.

Fig. 7 is a fragmentary detail in end elevation of the inner corner of one of the end frame structures of the swinging section showing the relation of the sections and the connecting link.

Before explaining in detail the present in-

vention, and the method or mode of operation embodied therein, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention beyond the terms of the several claims hereto appended or the requirements of the prior art.

In the drawings, wherein like reference numerals designate corresponding parts in the several views, A represents as a whole the main bed section and B the swinging or movable bed section. The main bed section is provided with the usual detachable bed ends 10 and 11, respectively, which comprise a substantially U-shaped frame work of any desired structure providing legs 10^a and 11^a having secured thereto adjacent their lower ends such as by welding or in any other suitable manner, brackets 10^b and 11^b.

The main bed section A comprises a pair of end members shown as a whole at 12 each including vertical side members 13, carrying at their lower ends casters 13^a, and upper and lower end rails 14 and 15 respectively, connected with the side members. A pair of side rails 16 and 17 serve to connect the end frames 12 and maintain them in spaced relation to receive a spring fabric shown as a whole at 18 which is connected to the end rails 14 in any suitable manner such as by springs 18^a. Each of the vertical side members 13 has attached thereto by means of rivets or the like a metal plate 19 provided with a stud or rivet 19^a which is adapted to engage the notch formed in the brackets 10^b and 11^b carried by the bed ends.

The swinging or movable bed section B comprises end frame members shown as a whole at 20 which are preferably in the form of substantially U-shaped members formed from a single angle bar and bent to provide vertical members 21 at the front side of the bed section, relatively shorter vertical members 22 at the rear side of the section B, and a horizontal portion 24, which latter portion serves as a head or foot extension for the bed section B and likewise as a handle member to permit the swinging section to be moved relative to the main section of the bed. Each end frame member also includes an end rail 23 which extends in a transverse direction parallel to the member 24 and is connected to the upright members 21 and 22 by means of rivets, bolts or the like 21^a and 22^a, respectively. The forward vertical members 21 carry at their lower ends casters 21^b which engage the floor and serve to support the front side of the bed sec-

tion B when it is in its fully extended position. A side rail 25 serves to secure the end frames 20 together and in fixed relation at the front side of the bed section. The rear vertical members 22 are connected together by a side rail 26 in a manner similar to which the members 21 are joined. It will be seen, Fig. 7, that the side rail 26 is connected with the vertical members 22 at a point directly below the bolt or the like 22^a marking the point of connection of the members 22 and the end rails 23, for a purpose to be fully described hereinafter. The bed section B carries the usual spring fabric shown as a whole at 27 which is detachably secured at opposite ends to the rails 23. It must be noted (Figs. 1 and 3) that the normal height of the bed is not increased when the sections A and B are together.

The swinging or movable bed section B is movably connected with the main section A at each end by means of a curved link member 30 pivotally connected at 31 to the lower transverse member 15 and at 32 to the transverse member 24 forming the head or foot extension of the section B, to permit it to be swung from the position of Fig. 1 to the position of Fig. 2 and vice versa; and by means of a swinging lever in the form of a relatively long link 33 having an offset upper portion 33^a and a bent lower end 33^b which is pivotally connected at 34 to the transverse member 15 at a point intermediate its ends, and at 35 to the upper inner end of the head or foot member 20. A substantially channel shaped member 36 is connected by means of rivets or the like 37 with the inner face of the link 33 at a point below the offset portion 33^a thereof and serves to support one end of a longitudinally extending truss member 38 which may be in the form of a pipe or tube. It will be understood that the members 30 and 33 are duplicated at opposite ends of the bed sections and that the opposite end of the structural member 38 is connected with a member similar to the member 36 at the other end of the bed sections so that movement of the link connections at either end of the bed imparts a similar movement to those members at the opposite end of the bed. Equalizing coil springs 39 and 40 are preferably interposed between the vertical side members 13 and the link 33, the ends of the coil springs being detachably connected with the members 13 and 36 respectively. These springs assist in the movement of the bed section B during the swinging operations.

The purpose of providing a relatively long lever or link 33 at each end of the bed is to increase the leverage and enable the link to be pivotally connected with the head and foot extensions 20 at their highest point at the inner side of the section B so that when the sections are closed together with the section B overlying the section A as shown in

Fig. 1, the link 33 will lie in a substantially vertical plane. The levers or links 33 perform two very important functions, namely, by serving as rigid supports for the inner side of the swinging bed section B when in either of the positions shown in Figs. 1 and 2, and likewise by supporting the section B in a position enabling it to be swung to an extended position by simply exerting a direct outward pull upon the section by grasping the head or foot extensions which serve as handles for moving the section, rather than an upward or lifting operation in addition to the outward pulling or swinging operation of the bed section which has heretofore been necessary with all of the swinging type day bed constructions. Moreover, by providing links 33 which are offset throughout a portion of their length, it will be seen that as the bed section B is swung from one position to another the link does not bind on the head or foot extension and leaves a free working joint at the pivotal points 35. It is important that the side rail 26 be connected to the vertical members 22 at a point immediately below the point of connection between the end rail 23 and the member 22. This point is designated by the reference numeral 22^a, and is likewise directly below the inner side or edge of the spring fabric 27. The pulling strain or force exerted by the fabric upon the end rails 23 is transmitted directly to the side rail 26, thereby eliminating any possibility of binding at the pivotal points 35. The construction of the links 33 and the location of the side rail 26 so as to enable the swinging section to have a free and easy movement, are very important features of our invention.

In Figs. 3, 4, and 5 we have shown an improved mattress particularly adapted for use in connection with our new and improved bed construction. The mattress is shown as a whole at 40 and comprises a pair of separate mattress sections 41 and 42, one for each of the bed sections A and B. The sections 41 and 42 are joined together at 43 to provide a flexible hinge or connection permitting the section 42 to be swung over onto the section 41 as indicated by the arrow in Fig. 4. The section 41 of the mattress, namely that section which covers the spring fabric of the swinging section B, is provided with pockets at opposite ends designated as a whole at 44. These pockets are formed by extending the mattress covering 45 beyond the ends of the mattress section 41, or they may if desired be in the form of separate flaps stitched to the ends of the mattress covering 45. These pockets 44 serve to enclose the head and foot extensions of the bed section B and are provided with depending flaps or extensions 44^a which serve to cover the end frame structure of the bed section B when this section is in its extended position (Figs. 2 and 4) and

the frame construction at the ends of both sections A and B when the bed is in the position in which it is shown in Figs. 1 and 3. It will also be understood that the covering 5 has an extension on front flap 45^a covering the remaining frame structure.

Aside from serving to cover the head and foot extensions, the pockets 44 serve to maintain the mattress section 41 in position upon 10 the bed section B against relative lateral displacement. In this connection it is pointed out that the head and foot extensions 20 serve to prevent lengthwise or longitudinal stretching of the mattress as well as to maintain it 15 in position upon the spring fabric 27 against longitudinal displacement.

Assuming that the bed is in the position in which it is shown in Figs. 1 and 3 and that it is desired to extend the bed to a full double 20 size, the operator grasps either of the head or foot extensions 20 and by applying a direct outward pull, the section B is caused to swing about the pivotal connections 31, 32, 34 and 35 and move outwardly relatively to the fixed 25 bed section A, the springs 39 and 40 assisting in this movement. After the bed section B has nearly reached its outermost position, the casters 21^a engage the floor and, together with the legs 21, serve to support the forward 30 side of the bed section, the side rails 17 and 26 overlapping in this position of the sections, thereby serving to support the inner side of said section. The head and foot extensions of the bed are of a sufficient height to 35 enable them to be grasped by the operator without the necessity of bending over. Since it is unnecessary for the operator to bend over to grasp the head or foot extension due to the height thereof, and moreover since the 40 links 33 are in a substantially vertical position at all times, it will be readily understood how it is possible to extend the bed section B by merely exerting a slight pull outwardly in a horizontal plane to so adjust the bed. 45 After the section B has been extended, the mattress section 42 is swung from its position overlying the section 41 to a position overlying the spring fabric 18.

To close the bed, the mattress section 42 is 50 moved in the direction of the arrow (Fig. 4) until it overlies the section 41, whereupon the operator grasps either of the combined head or foot extensions and handle members 20 and by applying a slight pressure thereto in 55 a substantially horizontal plane, the section B is caused to move the links 30 and 31 about their respective pivots until the side rail 25 engages the forward frame structure of the 60 main bed section A, in which position the sections are together as seen in Figs. 1 and 2.

We claim:

1. In a bed structure, a main bed section comprising end frames each including vertical side members and upper and lower trans-

verse members, a spring connecting the upper transverse members, a swinging bed section comprising end frames including upright structural members and transverse end rails connecting the upright members, a spring 70 fabric supported between said end rails, a side rail connecting the end frames of the swinging section at the inner side thereof directly below the point of connection of the transverse end rails and the upright members 75 at the inner side of the section, said end frames having head and foot members extending above said end rails, and a swinging link at each end of the bed sections connecting the lower transverse member and the head or foot members adjacent the inner end 80 thereof, said side rail serving to resist the pull of the spring fabric thereby relieving the pivotal connections between the swinging links and the head and foot members of strain to permit of a free swinging connection between said links and said extensions.

2. In a bed structure, a main bed section comprising end frames each including vertical side members and upper and lower transverse members, a spring connecting the upper transverse members, a swinging bed section comprising end frames including upright structural members and transverse end rails connecting the upright members, a spring 90 fabric supported between said end rails, a side rail connecting the end frames of the swinging section at the inner side thereof directly below the connection between the transverse end rails and the upright members 95 at the inner side of the frame, said end frames having head and foot extensions above said end rails and spring, and a relatively long swinging link having an offset portion connected at its lower end with the lower transverse member and at its opposite end with the head or foot extension at its inner upper corner, said side rail receiving the strain imparted to the frame by the spring fabric, thereby relieving the swinging link of any 100 pulling strain permitting a free swinging connection between the upper end of the link and the head or foot extension.

In testimony whereof we affix our signatures.

GEORGE BROWN.
FREDERICK S. BROWN.
